UNITED STATES PATENT OFFICE.

STANLEY A. PETTIBONE, OF CHICAGO, ILLINOIS.

DESIGN FOR A LAMP FIXTURE.

Application filed November 12, 1928. Serial No. 28,848. Term of patent 14 years.

To all whom it may concern:

Be it known that STANLEY A. PETTIBONE, citizen of the United States, residing at Chicago, in the county of Cook and State of Illinois, has invented a new, original, and ornamental Design for a Lamp Fixture, of which the following is a specification, reference being had to the accompanying drawing, forming part thereof.

The figure is a view in elevation of a lamp fixture, showing my new design.

I claim:

The ornamental design for a lamp fixture as shown.

In testimony whereof I affix my signature.

STANLEY A. PETTIBONE.
